UNITED STATES PATENT OFFICE.

FRED E. LOVEJOY, OF OLDTOWN, MAINE.

HOLDBACK-IRON.

1,100,590.

Specification of Letters Patent. Patented June 16, 1914.

Application filed September 3, 1913. Serial No. 787,961.

To all whom it may concern:

Be it known that I, FRED E. LOVEJOY, a citizen of the United States, residing at Oldtown, in the county of Penobscot and 5 State of Maine, have invented new and useful Improvements in Holdback-Irons, of which the following is a specification.

This invention is an improved hold back iron for attaching breeching straps of a harness to vehicle thills and permitting the breeching straps to be released from the thills in the event that the swing-tree or 10 traces break and the horse should start to run away, and thus prevent the vehicle or 15 its occupants from being injured, the object of the invention being to provide an improved device of this character which comprises a base member or attachment to a thill, a connecting member slidably and 20 detachably connected to the base member and which can be released from the base member by being drawn forwardly therefrom and a yielding locking member to secure the connecting member to the base member against 25 casual detachment and prevent said members from rattling, the invention consisting in the construction, combination and arrangement of devices hereinafter described and claimed.

30 In the accompanying drawings; Figure 1 is a side elevation of my improved hold back iron with the parts assembled and showing the base member in place on a thill and indicating the connecting member attached to a 35 breeching strap. Fig. 2 is a similar view with the parts disassembled. Fig. 3 is a vertical longitudinal central sectional view of the same with the parts assembled. Fig. 4 is a vertical transverse sectional view of 40 the same. Fig. 5 is a detail plan of the base member.

The base member 1 of my improved hold back iron is adapted to be placed on one of the thills of a carriage or other vehicle and 45 to be secured thereto by suitable screws, openings 2 being provided in the said base member for the reception of such screws. The base member is provided on one side with a longitudinal tongue 3 which projects 50 therefrom and is of less length and width than the base member, and at the rear end of the tongue the base member is formed with laterally extending stop shoulders 4. The front ends of the tongue and of the base 55 member are here shown as rounded or semi-circular in form and the tongue is undercut

and provided at its sides with longitudinal grooves 5. In the center of the tongue is a longitudinal recess 6 in which is a bent spring 7, the ends of the spring being secured in slits 8 at the ends of the said recess, the combined length of the recess and the slits being less than that of the spring so that the latter is buckled or bent outwardly at the center and its bent portion is 65 caused to project normally beyond the outer surfaces of the tongue as will be understood.

The attaching member 9 is formed on its outer side with an eye 10 to which a breeching or hold back strap may be attached as indicated in Fig. 1. The attaching member is provided on the side opposed to the base member with a longitudinal groove 11 for the reception of the tongue of the base member, flanges 12 being formed at the sides of 70 said groove to enter the undercut grooves 5 of said tongue. Hence the tongue and groove of the base member and attaching member coact to slidably connect the attaching member to the base member and to permit them to be readily detached by drawing the attaching member forwardly and prevent the attaching member from being drawn laterally from the base member. 80

When the attaching member is in place on the base member the rear ends of the side walls of its groove 11 and here indicated at 13 bear against the stop shoulders 4 of the base member thus preventing the attaching member from being drawn rearwardly 90 from the base member. The front of the groove 11 also forms a stop 14 which bears against the front end of the tongue 3 of the base member. In the inner side of the attaching member, at a point opposite the center of the spring 7 is a locking recess 15 with which the central bowed or bent portion of the spring 7 engages when the members of my hold back iron are assembled, the 100 said spring thus forming a yieldable locking member to secure it to the base against casual detachment therefrom but to permit the attaching member to be laterally drawn forward and detached from the base member and the said spring also serves to prevent the parts of the hold back iron from rattling.

I claim:

The herein described hold back iron comprising a base member for attachment to the thill and a connecting member for attach- 110

ment to a breeching strap, said base member having a longitudinal tongue on its upper side, undercut at its sides, said tongue having a longitudinal recess in its upper side, an outwardly bowed spring arranged in the said recess, and the said connecting member having a longitudinal groove in its under side, corresponding cross sectionally with the tongue and adapted to receive the same to slidably connect said members together, said grooves being closed at the rear end to provide a stop to coact with the rear end of the base member to limit the longi-

tudinal movement of the attaching member forwardly, said attaching member also having a recess in its inner side to receive the bowed portion of said spring and enable the latter to lock said members together against casual rearward movement of the connecting member and against rattling. 15 20

In testimony whereof I affix my signature in presence of two witnesses.

FRED E. LOVEJOY.

Witnesses:

STANLEY A. FISH,
GUY MAC PHEE.
